UNITED STATES PATENT OFFICE.

HARRY SHOEMAKER, OF JERSEY CITY, NEW JERSEY, ASSIGNOR OF ONE-HALF TO CORNELIUS D. EHERT, OF PHILADELPHIA, PENNSYLVANIA.

TACHOMETER.

No. 854,437.

Specification of Letters Patent.

Patented May 21, 1907.

Application filed July 30, 1906. Serial No. 328,371.

To all whom it may concern:

Be it known that I, HARRY SHOEMAKER, a citizen of the United States, residing at Jersey City, in the county of Hudson and State of New Jersey, have invented a new and useful Tachometer, of which the following is a specification.

My invention relates to tachometers and more especially that type involving electro-dynamic action.

It is the object of my invention to provide a tachometer, operating upon electro-dynamic principles, that shall have relatively great torque.

In tachometers heretofore known conducting disks or cylinders have been caused to deflect or rotate when acted upon by a magnet. While such construction is productive of certain results, I have found by experience that relatively much greater torque can be obtained by using in place of the conducting disk or cylinder a magnetizable member carrying a winding, preferably short circuited, so that relatively great currents are induced in well defined paths. Such construction has further advantages in that the instrument is practically aperiodic and extremely sensitive and constant in its calibration.

For an illustration of one form that my invention may take reference is to be had to the accompanying drawing, in which:

Figure 1 is a side elevational view of a manual tachometer, such as employed for measuring the speed of shafts, etc. Fig. 2 is a vertical sectional view, the handle omitted. Fig. 3 is a plan view of the magnet system. Fig. 4 is a plan view, partly in section, of the deflecting element. Fig. 5 is a partial elevational view, partly in section, taken on the line A B of Fig. 2. Fig. 6 is a view, partly in section and partly in elevation, showing the tachometer supplied with a flexible shaft and having the magnet system the indicating member. Fig. 7 is a plan view of the indicating magnet member shown in Fig. 6.

Referring to the drawing, 1 is a cylindrical casing of metal, preferably brass, mounted upon the end plates 2 and 3, preferably of brass. The screw threaded stud 4, on the plate 3, serves for securing the handle 5.

The sleeve member 6 is secured to and extends outwardly from the plate 2 and is bored to form a bearing for the shaft 7,

pointed at 8 to engage in the center hole of a shaft or the like. A collar 9 is secured upon the shaft 7, a ball bearing intervening between it and the end of the sleeve 6. At its inner end the shaft 7 is slightly reduced in diameter and extends through the magnet system 10 which is secured thereto by screw 11. The magnet system consists of a plurality of radial portions 12 which terminate in portions 13 extending at right angles and constituting pole pieces. As shown in Fig. 3, there are eight poles, neighboring poles 65 being of opposite signs. Any other number of poles may be used. Such magnet system may be made out of a single steel forging properly machined, and the inner surfaces 13' of the pole pieces being turned true about 70 the shaft 7. The system is then magnetized and thoroughly aged. The shaft 7 and the magnet system 10 constitute the rotating element of the tachometer.

The indicating element or partially rotatable element is the member 14, whose periphery is turned true about its pivotal support and concentric with the inner faces of the poles 13 of the magnet system, the air gap between the magnet poles and the member 80 14 may be as small as possible consistent with mechanical considerations. The body of member 14 is made up of laminae of iron or soft steel laid side by side. Numerous tunnels are drilled or punched horizontally 75 near the periphery and narrow slots 15 sawed through from the periphery to the tunnels. In the tunnels are laid bars 16 of copper or other suitable conducting material, such as silver or manganin, and these bars extend 85 also through the end plates 17 to which they are thoroughly electrically and mechanically connected. The inner portions of the member 14 are cut away except the supporting arm 18, through which is secured the hub 19, 95 and the counterpoise portion 20. Extending through the hub 19 is the pivotal shaft 21 having a cone bearing at each end. One cone point bears in a socket in the screw 22 which passes through the plate 23 into the 100 plate 3. Another screw 24 passes through the plate 23 into the plate 3. The post 25 is secured by a screw 26 to the plate 23, and secured by a screw on the outer end of the post 25 is the arm 26' carrying at its outer end the 105 screw 27 having a socket to receive the other

conical point of the pivotal shaft 21. The member 14 is therefore capable of rotating through nearly an entire revolution, complete revolution being prevented by the arm 18 engaging the post 25 in either direction. The axis of the pivotal shaft 21 coincides exactly with the shaft 7 and therefore with the magnetic system.

To control and oppose the movement of the member 14 a cord or wire 28 is wrapped several times around the pivotal shaft 21, the ends being connected to helical or other springs 29 and 30, the former secured to the end of the arm 31, the latter to the end of the arm 32. The arms 31 and 32 are pivoted at 33 and 34 respectively on the member 35 by the screw 37 extending loosely through the casing 1 and engaging with its inner end the tails of the arms 31 and 32. A spring 38 secured upon the plate 3 holds the member 35 tilted against the screw 39 engaging in the casing 1.

A scale plate 40, cylindrical in shape, is supported by arms 41 upon the deflecting member 14 and carries on its outer surface graduation marks 42 which appear before the opening or window 43 in the casing 1, a mark 44 in the window 43 serving as the zero or reading mark.

The operation is as follows: With the parts at rest the springs 29 and 30 hold the deflecting member 14 centralized; that is, the post 25 extends through the space between the counterpoise 20 and the rim of the member 14. The instrument is grasped by the handle 5 and the point 8 is inserted in the center mark in a rotating shaft, or the like, whose speed is to be measured. The magnet system 10 is rotated at the same speed as the shaft, the thrust being taken up by the ball bearing. By the relative motion of the magnet system and the deflecting member 14, currents are induced in the winding, composed of the bars 16 and the end plates 17, and member 14 tends to follow the magnet system. If there were no opposition member 14 would rotate at a speed just slightly below that of the magnet system. However, rotation is opposed by the springs 29 and 30 which are suitably proportioned to the torque exerted by the member 14 when the magnet system 10 is rotating at or beneath a predetermined speed. Member 14, because of the torque it exerts, will be compelled to stretch either the one or the other of the springs 29 and 30 so that its angular displacements will be proportional to the torque it exerts. In so moving member 14 carries the scale plate 40 past the mark 44 in the window 43 and the operator reads directly the speed of the shaft, the scale marks 42 having been first obtained by calibration tests. During calibration the proper tension upon the springs 29 and 30 is obtained by adjusting the screw 37. If at any time, as subse-

quent to calibration, the zero of the instrument should change for any cause it can be properly brought back, without destroying the calibration of the instrument, by the screw 39 and the spring 38 which will tilt the member 35 to proper position.

The indicating element of the tachometer comprising a winding causes relatively great torques in apparatus of small dimensions, so that long range instruments are available whose constancy in calibration is obtained and whose sensitiveness is of the greatest. And such winding renders the instrument highly aperiodic.

While in the foregoing figures I have shown the tachometer in the form of a manual instrument, it is to be understood that it may assume other forms, as, for example, as shown in Fig. 6, where the shaft 7 is driven by a flexible shaft 45 housed within a flexible casing 46. At its upper end the shaft 45 connects with the shaft 7, and the flexible casing 46 connects with the shell 47 screw threaded on to the sleeve 6. A similar shell member 48, fastened upon the lower end of the flexible casing 46, is adapted to be held in a suitable clamp secured upon an automobile or other body and has a bearing for the pinion 49, secured to the lower end of the flexible shaft 45. This pinion engages with the gear 50 mounted upon the axle or other suitable member of an automobile or the like. The gear 50 then drives the pinion 49 which communicates rotation through the flexible shaft 45 to the shaft 7. Within the case of the instrument the magnetizable member 14 carrying a squirrel-cage winding, is secured upon the end of the shaft 7 and rotated thereby. The member 14 is similar to that shown in Fig. 4 except that it need not have cut-away portions nor a counterbalance 20. In fact, the rotating magnet system and the indicating member are simply interchanged, the magnet system being the relatively stationary member capable of limited movement upon the shaft 21 and controlled, as is the magnetizable member in Fig. 2. It is obvious that either the magnet system or the magnetizable member carrying the winding can be made the rotating member. When the magnet is made the indicating member, it is cut away as shown in Fig. 7 at 51 and a counterbalance 52 is provided.

What I claim is:

1. In a tachometer, a rotatable magnet system, a magnetizable mass carrying a winding associated with and in the field of said magnet system, indicating means carried by said magnetizable mass, and means for opposing the movement of said magnetizable mass.

2. In a tachometer, a rotatable magnet system, a magnetizable member carrying a squirrel-cage winding associated with and in the field of said magnet system, indicating

- means carried by said magnetizable member, and means for opposing the movement of said magnetizable member.
3. In a tachometer, a rotatable magnet system, a magnetizable mass mounted concentrically therewith for limited movement, a short circuited winding disposed upon said magnetizable mass, and indicating means carried by said magnetizable mass.
- 10 4. In a tachometer, a rotatable magnet system, a relatively stationary indicating member comprising a short circuited winding, and means opposing the movement of said indicating member.
- 15 5. In a tachometer, the combination with an indicating element of means for opposing the torque of said element comprising a spring operating tangentially upon the shaft of the indicating element, means for adjusting the tension of said spring, and means carrying said adjusting means and itself adjustable to vary the zero of the instrument.
- 20 6. In a tachometer, a multipolar permanent magnet constituting a rotatable magnet system, an indicating member comprising a magnetizable mass carrying a short circuited winding and disposed in the field of said magnet system, indicating means carried by said indicating member, and means for opposing the movement of said indicating member.
- 25 7. In a tachometer, a rotatable magnet system, an indicating member comprising a magnetizable mass carrying a short circuited winding and disposed in the field of said magnet system, means for opposing the movement of said indicating member, and means for adjusting the zero of the instrument.
- 30 8. In a tachometer, the combination with a rotatable magnet system, of an indicating member capable of limited movement and comprising a magnetizable mass carrying a short circuited winding and disposed in the field of said magnet system, a spring for opposing the movement of said indicating member, means for adjusting said spring, and means for varying the zero of the instrument.
- 35 9. In a tachometer, the combination with a rotatable magnet system, of a relatively stationary indicating member comprising a magnetizable mass carrying a short circuited winding and disposed in the field of said magnet system, a shaft supporting said indicating member, opposing springs operating tangentially upon said shaft, and means for adjusting the tension of said springs.
- 40 10. In a tachometer, the combination with a rotatable magnet system, of a relatively stationary indicating member comprising a magnetizable mass carrying a short circuited winding and disposed in the field of said magnet system, a shaft supporting said indicating member, springs operating upon said shaft to oppose the movement of said indicating member, means for adjusting said springs, and means for varying the zero of the instrument.
- 45 11. In a tachometer, the combination with a rotatable magnet, of an indicating member comprising a ring of magnetizable material disposed in the field of said magnet, a winding carried by said ring, means for opposing the movement of said ring, a shaft, an arm supporting said ring upon said shaft, and a counterpoise operating to balance said arm about said shaft.
- 50 12. In a tachometer, the combination with an indicating element, of means for opposing the torque of said element, means for adjusting said opposing means, and means carrying said adjusting means and itself adjustable to vary the zero of the instrument.
- 55 13. In a tachometer, the combination with a rotatable magnet, of an indicating member comprising a ring of magnetizable material disposed in the field of said magnet, a winding carried by said ring, a shaft, an arm supporting said ring upon said shaft, means for opposing the movement of said ring, a counterpoise for balancing the ring member about said shaft, and a post for supporting said shaft extending through said ring, there being a gap between said counterpoise and ring.
- 60 14. In a tachometer, the combination with an indicating element, of means for opposing the torque of said element comprising a spring, a lever to which said spring is secured pivoted upon a carrying member, and means for adjusting said carrying member to vary the zero of the instrument.
- 65 15. In a tachometer, the combination with an indicating element, of a shaft supporting the same, opposing springs operating upon said shaft to oppose the movement of said indicating element, each spring secured to a pivoted lever, means for adjusting said levers to change the tensions of said springs, a member carrying said pivoted levers, and means for adjusting said carrying member to vary the zero of the instrument.
- 70 16. In a tachometer, the combination with a rotatable permanent magnet, of an indicating member comprising a ring of magnetizable material having relatively slight radial depth and disposed in the field of said magnet, a short circuited winding disposed thereon, and means for opposing the movement of said indicating member.
- 75 In witness whereof I have hereunto affixed my signature in the presence of the two subscribing witnesses.
